UNITED STATES PATENT OFFICE.

CELESTINO MAZZUCHELLI, OF COMO, ITALY.

METHOD FOR WINDING SILK ON SPOOLS AND MACHINE FOR CARRYING OUT THIS METHOD.

1,267,099.

Specification of Letters Patent.

Patented May 21, 1918.

Application filed December 15, 1913. Serial No. 806,816.

To all whom it may concern:

Be it known that I, CELESTINO MAZZUCHELLI, a subject of the King of Italy, residing at Como, Via Briantea 1, Italy, have 5 invented new and useful Improvements in Methods for Winding Silk on Spools and Machines for Carrying Out These Methods; and I do hereby declare the following to be a full, clear, and exact description of the 10 invention, such as will enable others skilled in the art to which it appertains to make and use the same, reference being had to the accompanying drawings, and to letters or figures of references marked thereon, which 15 form a part of this specification.

This invention relates to an improved method for winding silk on spools and to a machine for carrying out this method.

In the hitherto known winding machines 20 there are to be found two different methods for rotating the spools. According to one of these methods the spool is fixed upon an iron spindle and it is carried together with this spindle by a bifurcated support. The 25 support, or the spool, is then pressed against a rotating pulley, so that the spool is rotated by the friction produced with a uniform peripheral velocity, which corresponds to that of the pulley.

According to the second known method 30 the spool is pushed onto a spindle having at one end a head with a diameter of $1\frac{1}{4}$ - $1\frac{3}{4}$ inches; this head is brought in contact with a small pulley, whose width corresponds to 35 that of the spindle head. The friction produced causes a rotation of the spindle and therefore also of the spool. According to this method the peripheral velocity of the spool increases gradually with the increasing 40 diameter of said spool, while the silk is wound upon the latter.

Both these known methods have, however, the following drawbacks: The angular velocity of the reel does not remain absolutely 45 the same. If, for instance, the thread is not loosened in the proper manner from the strand, the spool, or the spindle head slips on the pulley and the reel is brought to a standstill till the increased pull loosens the

thread, whereupon the reel is again rapidly 50 rotated. Since the reel has, however, a much greater diameter than the spool its gyrating mass imparts to this reel suddenly a greater velocity. During this period the thread is wound on the spool in a slack manner. 55 Hereupon the angular velocity of the reel decreases gradually till it corresponds again to that of the spool. During this period the thread is wound up in a tight manner. 60

These periods change continually in an irregular manner, so that the thread is wound up sometimes in a slack and sometimes in a tight manner.

According to the method of the present 65 invention the thread leaving the reel is not fed directly to the spool, but passes at first around a large drum, acting as a guide for the thread and serving at the same time for driving the spool. After the thread has been 70 passed once around said thread-guiding drum it is wound in a known manner on the spool; the hereinbefore mentioned drawback being thereby entirely eliminated.

The invention relates further to brake- 75 means for the reel provided on a machine for carrying out this improved method, to means for carrying the thread once around the drum while this machine is stationary, and to means for stopping the machine as 80 soon as the thread breaks or as soon as a spool is wound up.

A convenient mode of carrying the invention into effect is shown by way of example in the accompanying drawings in which: 85

Figure 1 shows a front elevation of the winding machine, there being omitted several parts on the left hand side of the machine for the sake of clearness;

Fig. 2 shows a plan sectional view on the 90 line A—A of Fig. 1, some further parts being omitted for the sake of clearness;

Fig. 3 shows on an enlarged scale a front elevation of a part of the machine;

Fig. 4 shows a detail,

Figs. 5 and 6 show in front and plan view a further detail and

Fig. 7 shows a modification of a detail.

In the illustrated machine 1 denotes the reel from which the silk thread 2 is reeled off. The thread drawn off the reel passes then over a thread-guide 3, and if one wishes to clean at the same time the silk, said thread is also passed through a cleaning appliance 4. Hereupon the thread 2 is passed directly onto a large feed drum 5. 6 denotes the spool, the spindle of which is supported in 10 a bifurcated lever 7 pivotally connected to a frame part 8. The lower end of this lever 7 carries a weight which has the tendency to rotate the lever 7 in a counter-clockwise direction, thus pressing the spool 6 against the drum 5, so that sufficient adhesion is imparted to the thread to remain in contact with said drum 5. The thread passes, while an equal tension is exerted upon it once around said drum and it then 20 crosses the thread reeled off the reel 1 to be fed over a thread guide 9 mounted on the small pivotally arranged lever 10 and the thread guide 11, fixed to the reciprocating thread guide rod 12 and it is then finally 25 wound upon the spool. From the foregoing it is evident, that the hereinbefore mentioned irregularities in the thread tension are only transmitted up to the point, where the spool 6 is pressed against the drum 5, which acts 30 not only as a driving means for the spool, but serves at the same time to guide the thread 2. From said point the thread 2 is passed with equal tension once around the drum 5. At the point where the thread leaves 35 this drum the tensions in the thread are completely equalized.

The thread guides 3 and 9 are disposed in such a manner that the threads do not touch one another at the crossing point. 40 This arrangement permits very thin silk threads to be reeled off and wound up with much greater velocities than heretofore.

For each thread guide drum 5, there is provided a rope drive 13 transmitting the drive 45 from the main driving shaft 14 to a pulley 5^a mounted on the same shaft as said drum. Adjacent to each pulley 5^a there is provided a brake disk 5^b.

The drums 5 are carried by bifurcated 50 levers 15 pivotally connected at 16 to the machine frame 17. To these levers 15 are pivotally connected the bell crank levers 18, which effect in their different positions a stoppage or running of the machine. The 55 lower end of each bell crank lever 18 rests on the abutment 19 of the machine frame. If the lever 18 is in the position shown in Fig. 3 the rope drive 13 is tensioned and the thread guiding drum and driving pulley 5^a is rotated.

In order to stop the machine when the thread is broken or to pass the thread around the pulley 5 the handle of the locking lever 18 is moved in the direction of the arrow

B shown in Fig. 3, the lower end of this 65 lever being then lifted. Owing to the action of its own weight the drum 5 the brake disk 5^b is now pressed against the brake shoe 20 pivotally attached at 37 to the machine frame. This causes a slackening of the rope 70 drive 13 and the drum 5 is therefore brought to a standstill.

On the supporting lever 7 carrying the spool 6 there is provided a nose 21 (Fig. 3) and on a bracket-like part of the machine 75 frame 17 is pivotally attached a lever 22. For the purpose of changing the spool 6 or of knotting a broken thread the lever 7 is rotated in the direction of the arrow C shown in Fig. 3 till said nose 21 engages the catch 80 lever 22.

In order to put the thread guiding drum 5 again in motion the lever 15 is moved in the direction of the arrow B shown in Fig. 3 till the lower end of the lever 18 rests on the 85 abutment 19, the rope drive 13 being then tightened as soon as the parts are again in the position shown in Fig. 3.

Fig. 4 illustrates a part of the rim of the thread-guiding drum 5 in its natural size. 90 As shown in this figure there is pivotally connected to the inner rim part a lever or catch 23 provided with a bolt 24 projecting in a hole 25 of said drum 5. The lever 23 is acted upon by a flat spring 26 normally preventing said bolt 24 from projecting beyond the circumference of the drum 5.

For the purpose of guiding the thread 2 around the drum 5 at the beginning of the winding operation and when the machine is 100 still stopped, the lever 23 is pressed by hand against the action of the spring 26 toward the rim, so that the bolt 24 is brought to project beyond the circumference of the drum 5. The thread reeled off the reel 1 and passing over the guide 3 and between the cleaner 4 is wound several times around the bolt 24. The catch 23 is now released, whereupon the bolt 24 with the thread wound around it is moved back into the position shown in Fig. 105 4. After the drum 5 has been rotated once by hand the thread 2 is taken off the bolt 24 and passed over the guides 9 and 11 to be wound upon the spool 6. At the same time the outer end of the lever 22 is pressed downward in the direction of the arrow D shown in Fig. 3, so that it comes out of engagement with the nose 21 and the supporting lever 7 carrying the spool 6 is again pressed against the drum 5 in order to rotate said 115 spool 6.

I shall now describe the means for stopping the machine as soon as the thread 2 breaks. To the shorter end of the hereinbefore mentioned oscillating lever 10 there is 120 attached a vertical rod 27 guided at its lower end in a support 28 carried by the machine frame 17. On the lower end of the rod 27

there is provided a stop or collar 29. To a sleeve like projection provided on the lower end of the lever 18 there is pivotally attached at 30 a short lever 31 resting on an eccentric disk 32. The axis 33 on which are mounted the eccentric disks 32 receive its drive from the main driving shaft 14 by means of a rope drive 34.

As soon as a thread is broken, the thread 10 guide 9, normally held down by the thread tension, is raised by the vertical rod 27 which drops; the collar 29 provided on this rod is therefore lowered and owing to the action of the spring 36 upon said rod it is 15 moved beneath the stop 35 of the support 28. The continually rotating eccentric disk 32 causes a continual up and down movement of the short lever 31. As soon, however, as the rod 27 has been lowered the right hand 20 end of said lever 31 strikes against the lower end of the rod 27, so that said end of the lever is prevented from further moving and the opposite end with its pivot 30 will now be raised. This brings the lower end 25 of the bell crank lever 18 out of engagement with the stopping traverse 19 and the weight of the drum 5 causes the latter to swing in an anticlockwise direction, so that its brake disk 5^b is brought in contact with the brake 30 shoe 20 oscillating around the pivot 37. A further rotation of the drum 5 is then prevented.

To the other end of the brake shoe 20 there is connected a vertical rod 38, which is 35 bifurcated at its upper end and reaches normally nearly up to the grooved hub 42 of the reel 1 without, however, touching said hub 42. The axis 39 of the reel 1 (Figs. 5 and 6) is supported at both ends (in the figures 40 there is shown only one end of this axis) by rollers 40 carried by a frame 41. This secures a very easy running of the axis 39 of the reel 1, the resistance produced being very small. When the brake disk 5^b provided on the same axis as the drum 5 touches the brake shoe 20, the vertical rod 38 is raised, so that the reel 1 is also raised and prevented from turning owing to brake action 45 exerted by said rod 38 upon the hub 42. Owing to the fact that a brake action is exerted upon the reel 1 as soon as the thread is broken, this broken thread cannot entangle when the reel is further rotated; on the contrary said broken thread can 50 easily be found.

I shall now further describe how the machine is stopped when the spool 6 has been wound up, *i.e.* when the spool 6 has the desired thickness. As the diameter of the 55 spool 6 increases, the supporting lever 7 is moved in the direction of the arrow C shown in Fig. 3, so that the lower end of this lever is raised. When sufficient thread has been wound upon the spool 6 the lower end of

said lever 7 strikes against the pin 43 (Fig. 65 3) provided on the lower end of the bell crank lever 18. The latter is therefore brought out of engagement with the abutment 19, so that the brake disk 5^b is brought 70 in contact with the brake shoe 20. This causes a stoppage of the drum 5 and of the reel 1.

In the hereinbefore description there has been mentioned only one reel and one thread guiding drum, but I wish it to be clearly 75 understood that there are provided on each machine several groups of such reels and drums, as shown in Fig. 2, actuated from a common driving shaft 14 but working for the rest independently one from another. 80

Fig. 7 shows a modification of the means for carrying the thread 2 once around the drum 5 when the machine is stopped. According to this modification the bolt or pin 24 around which the thread has to be wound 85 is acted upon by a flat spring 44 guided by means of pins 45 screwed into the rim of the drum 5. If the thread has to be wound around the pin 24 at the beginning of the reeling operation, the spring 44 is pressed 90 against the rim of the drum 5 to be released as soon as said operation is performed.

What I claim is:—

1. A thread winding machine comprising a thread feeding drum, and a thread holding device on the drum for drawing the thread around the latter at the beginning of the unreeling operation. 95

2. In a thread winding machine, a feeding drum, a thread holding member thereon 100 comprising a bolt arranged to be projected through the periphery of the drum, and a spring for normally holding the bolt retracted.

3. In a thread winding machine, a feeding 105 drum, a thread holding device comprising a lever pivoted on the inner periphery of the drum, a bolt on the lever adapted to be projected through the periphery and a spring acting on the lever to withdraw said 110 bolt.

4. In a thread winding mechanism the combination with a thread supporting reel, of a thread feed drum around which the thread is once passed, a pivoted lever supporting the drum, means to guide the thread onto and off of the drum, a drive for said drum drawing the thread from the reel, a winding-on spool arranged to receive the thread from the drum, means to yieldingly 120 hold the spool in contact with the drum to rotate said spool, a thread guide reciprocating in a direction parallel to the axes of said drum and guide, and means actuated by said spool holding means to permit the 125 drum to move out of driving contact with said spool when the latter is full.

5. The method of winding silk fiber

which comprises directing the fiber from the supply reel downward to a driving drum capable of swinging out of operative position and simultaneously bending the fiber 5 toward a vertical, said fiber passing around said drum and crossing the downwardly directed portion, thereafter directing the fiber to a spool frictionally driven by the contact of said drum with the fiber wound 10 upon the spool, the fiber being fed to the

spool substantially at the nip between the drum and spool.

In testimony that I claim the foregoing as my invention, I have signed my name in presence of two subscribing witnesses.

CELESTINO MAZZUCHELLI.
